(57) **CLAIM**

The ornamental design for a cloud-shaped lower body garment gusset panel, substantially as shown and described.

DESCRIPTION

FIG. 1 is a top rear perspective view of a cloud-shaped lower body garment gusset panel of the present invention, as it may be used in an undergarment (the broken lines shown on the cloud-shaped lower body garment gusset panel and on the undergarment represent unclaimed features);

FIG. 2 is a plan enlarged view of the claimed lower body garment gusset panel design;

FIG. 3 is a front elevational enlarged view of the claimed lower body garment gusset panel design;

FIG. 4 is a rear elevational enlarged view of the claimed lower body garment gusset panel design; and,

FIG. 5 is a right side elevational enlarged view of the claimed lower body garment gusset panel design (the left side elevational enlarged view is a mirror image thereof).

1 Claim, 2 Drawing Sheets
